DESIGN FOR A WRIST WATCH BEZEL

Richard Jaccarino, Tuckahoe, N. Y.

Application December 11, 1937, Serial No. 73,530

Term of patent 3½ years

To all whom it may concern:

Be it known that I, Richard Jaccarino, a citizen of the United States, residing in the county of Westchester, town of Tuckahoe, and State of New York, have invented a new, original, and ornamental Design for a Wrist Watch Bezel, of which the following is a specification, reference being had to the accompanying drawing forming part thereof.

Figure 1 is a top plan view of the bezel for a wrist watch, showing my new design.

Figure 2 is an end elevation of the bezel shown in Figure 2.

Figure 3 is a cross-section on line 3—3, Figure 1. In my new design the crystal follows the prismatic configuration of the top of the bezel.

I claim:

The ornamental design for a wrist watch bezel, as shown and described.

RICHARD JACCARINO.
